KNIFE HANDLE

Walter A. Kunze, Chillicothe, Ohio, assignor to Lincoln Manufacturing Company, Inc.

Filed July 29, 1971, Ser. No. 167,551

Term of patent 14 years

Int. Cl. D7—03

U.S. Cl. D95—3 R

FIG. 1

FIG. 2

FIG. 3

FIG. 4

FIG. 1 is a side view of a knife handle showing my new design;

FIG. 2 is a top view thereof;

FIG. 3 is an end view thereof as seen from the right of FIG. 1; and,

FIG. 4 is a perspective view thereof.

The side opposite that represented in FIGS. 1 and 4 is identical to that shown. The bottom of the knife handle has the appearance and configuration shown in FIGS. 1, 3 and 4.

I claim:

The ornamental design for a knife handle, substantially as shown and described.
